UNITED STATES PATENT OFFICE.

ALFRED B. ROSEBOOM, OF CHICAGO, ILLINOIS.

TOY.

1,400,696.

Specification of Letters Patent. Patented Dec. 20, 1921.

Application filed December 29, 1920. Serial No. 423,799.

To all whom it may concern:

Be it known that I, ALFRED B. ROSEBOOM, residing at Chicago, in the county of Cook, State of Illinois, a citizen of the United States, have invented a new and useful Toy, of which the following is a specification.

The object of my invention is to provide a new, simple and inexpensive toy. It is a further object of my invention to provide 10 a device of this class so designed as to represent, when in action, aerial performers. It is a further object of my invention to provide 15 a device of this class having figures pivotally and slidably mounted thereon in such a manner so that when one of the figures is thrown upwardly it is automatically caught and held by the hands of the other figure.

The above and other features of novelty, 20 advantages and capabilities will become apparent from the detailed description of the accompanying drawings, in which I have illustrated one embodiment of my invention, but the construction there shown is to be 25 understood as illustrative only, and not as defining the limits of my invention.

Figure 1 is a perspective view of a device embodying one form of my invention and Fig. 2 is a vertical sectional view of the 30 same, showing the slidably mounted figure held in its uppermost position by the hands of the pivotally mounted figure.

Referring to the drawings in detail, the base "10," which may be of any desired formation, has detachably secured thereto a standard "11," which standard at its lower end is screw threaded into a screw threaded opening in the base "10." The standard at its upper end is provided with a right angle 35 downwardly bent arm "12," which arm at its lower end is provided with a plurality of openings as best shown in Fig. 2. Surrounding the standard "11" and resting on the base "10" is a compression spring "13." Slidably mounted on the standard "11" and 40 normally resting on the spring "13" is a spring actuated figure 14, which figure is designed to represent an aerial performer having the same design on both sides, and 45 is stamped from a single piece of thin sheet metal with the metal at the back near the neck and the head cut away as at "15," with the back of the head and body formed integrally with the sides. The outstretched

hands of the figure 14 are connected together 55 by means of a small rod "16" as best shown in Fig. 1. Pivotaly mounted on the arm "12" in the openings as shown is a second figure "17" designed to represent a clown performer, which figure is likewise stamped 60 from a single piece of sheet metal, having both sides identically alike and connected together by means of the integral strip "18," which figure when mounted is normally in a horizontal position with outstretched legs 65 "19" and arms "20." In operating the device one pulls or presses downwardly on the figure 14, releasing it quickly, as a result of which the spring actuated means throws it upwardly on the standard "11" the head 70 "31" striking the legs "19" of the pivotally mounted figure "17" with sufficient force to throw such figure into the position shown in dotted lines in Fig. 2, bringing the arms "20" of such figure downwardly and inwardly into the path of the rod "16" on the figure 14, whereby said lower figure on its descending movement is automatically 75 grasped by the hands of the upper figure and held in raised position as shown in Figs. 80 1 and 2 until it is released by pressing slightly upwardly on the lower figure, or rather by raising the lower figure sufficiently to allow the upper figure to swing just enough to throw the hands "20" out of the 85 path of the descending rod "16." The greatest weight of the upper figure is to the right, in order to quickly swing the hands of the upper figure out of the path of the rod "16." To prevent the upper figure from 90 swinging too far to the right and thus hold it in position for proper reoperation when the lower figure is again shot into contact with the legs "19," the upper figure is mounted in such a manner as to cause the strip 95 "17" as best shown in Fig. 2 to contact with the arm "12" and thus limit the downwardly swinging movement of the legs "19." The upper figure can be adjusted to different positions by inserting the slidably pivot pin 100 "21" in any one of the different openings in the arm "12."

From this it will be seen that I have provided not only a simple, inexpensive, interesting and amusing toy for the children, but 105 also one which is additionally useful from a mechanical and educational standpoint. It will further be seen that all the parts are

detachable, and that it can be easily and quickly knocked down for shipment and readily set up for display or use.

Having thus described my invention what 5 I claim is:—

1. In the combination of a toy, a base, a standard, a figure designed to represent an aerial performer, slidably mounted on said standard, a second figure likewise designed 10 to represent an aerial performer pivotally mounted on said standard near the upper end, means for shooting said first figure upwardly into contact with the pivotally mounted figure and means on said second 15 figure designed to automatically grasp said second figure and hold it in raised position until released.
2. In a toy the combination of a standard, a spring, a figure slidably mounted on said 20 standard and adapted to be shot upwardly by said spring, a second figure pivotally mounted near the upper end of said standard, and provided with means to automatically grasp and hold in raised position said 25 first figure when said figure is shot into contact with said pivotally mounted figure.

3. In a toy the combination of a base, a standard detachably secured to said base, a compression spring surrounding said standard and normally resting on said base, a 30 figure slidably mounted on said standard and normally resting on said spring, said figure having outstretched arms connected together by means of a rod or the like, an inwardly and downwardly extending arm 35 on said standard provided with an opening, a second figure having outstretched hands and legs pivotally mounted on said arm and means for limiting the downwardly swinging movement of the legs of the pivoted figure, the said pivoted figure being so mounted as to cause the hands thereof to automatically grasp and hold in raised position the 40 lower figure when said lower figure is shot into engagement with the upper figure. 45

In witness whereof, I hereunto subscribe my name to this specification in the presence of two witnesses.

ALFRED B. ROSEBOOM.
